KNOB

Herbert J. Hampel, Philadelphia, and Milton L. Ross, Bala-Cynwyd, Pa.; said Hampel assignor to The Ross Manufacturing Company, Southampton, Pa., a corporation of Pennsylvania

Filed Apr. 14, 1966, Ser. No. 1,899

Term of patent 14 years

(Cl. 26—13)

FIG. 1

FIG. 2

FIG. 3

FIG. 4

FIGURE 1 represents a perspective view of a knob having the design of our invention.

FIGURE 2 represents a front elevational view of the knob illustrated in FIGURE 1.

FIGURE 3 represents a plan view of the knob illustrated in FIGURE 1.

FIGURE 4 represents a side elevational view of the knob illustrated in FIGURE 1.

The shading as appears on the drawing indicates color contrast.

We claim:

The ornamental design for a knob, as shown and described.
